UNITED STATES PATENT OFFICE.

FRANK BOWERS, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

SOOT BLOWER.

Application filed October 28, 1919. Serial No. 334,025.

This invention relates to boiler cleaners and refers more particularly to boiler cleaners of the type in which a unit having a plurality of discharge nozzles is preferably arranged so as to rotate about its axis and thus discharge the jets against the surface to be cleaned.

In boiler cleaners of this general type difficulty is encountered in placing the units in certain parts of the boiler owing to the excessive heat developed which will tend to destroy the unit. Also the unit must be so placed as to not interfere with the normal operation of the boiler. The present invention resides in the novel construction and location of the unit and in such further details of construction as will more fully herein-after appear.

In the drawings:

20 Figure 1 is a fragmentary side elevational view partly in section showing the arrangement of the blower unit.

Figure 2 is a view looking at right angles to Figure 1.

25 In detail A designates a boiler having headers B connected by a plurality of rows of tubes C. There is also a supplementary header D which is spaced from the header B and is connected thereto by water circulating pipes E. The blower unit F is positioned so that its nozzles F' extend between the tubes E and the unit is located within a recess or shelter portion H. This not only protects the unit but insures it being easily accessible through the door J.

30 In detail the unit F comprises a rotatable pipe L having a plurality of branches K which carry the discharge nozzles F'. These branches extend between the water circulating pipes E, thus permitting the blower unit and its mounting being located outside of the extreme heat zones of the furnace. The casing M which forms a supplemental housing for the pipe L also carries the bearings 45 N, and the entire mechanism with the exception of the inner ends of the pipes K is located in that portion of the boiler between the headers B and D and the door J. Suitable connections to a source of supply of 50 steam or other cleaning substance (not shown) will of course be employed.

What I claim as my invention is:

1. In a boiler structure, the combination with a header and a bank of boiler tubes extending from said header, of a series of water

circulation tubes extending from said header at an angle to said boiler tubes, a rotatable blower header extending transversely to and adjacent said water circulation tubes and a plurality of branch discharge pipes 60 projecting from said blower header between said water circulation pipes and adapted to discharge upon said boiler tubes.

2. The combination with a boiler having a 65 plurality of boiler tube headers, means connecting said headers affording water circulation therebetween and steam generating tubes extending into the boiler combustion chamber, of a cleaning fluid supply header, said boiler tube headers and connecting 70 means separating the cleaning fluid supply header from the boiler combustion chamber, so as to position the cleaning fluid supply header substantially free from contact with the boiler combustion chamber gases, said 75 cleaning fluid supply header having a branch pipe extending therefrom into the boiler combustion chamber and carrying a discharge nozzle likewise located within the boiler combustion chamber for discharging 80 a jet of cleaning fluid toward said steam generating tubes.

3. The combination with a boiler having a 85 plurality of spaced boiler tube headers, water circulating tubes connecting the headers and steam generating tubes extending into the boiler combustion chamber at an angle with the circulating tubes, of a cleaning fluid supply header located outside the boiler combustion chamber so as to be substantially free from contact with the hot combustion chamber gases, said cleaning 90 fluid supply header having a branch pipe extending therefrom between said water circulating tubes and into the boiler combustion chamber, and a cleaning fluid discharge 95 nozzle carried by the branch pipe and likewise located within the boiler combustion chamber for discharging a jet of cleaning fluid toward said steam generating tubes. 100

4. The combination with a boiler having a plurality of spaced boiler tube headers, water circulating tubes connecting the headers and steam generating tubes extending into the boiler combustion chamber at an angle with the circulating tubes, of a cleaning fluid supply header located outside the boiler combustion chamber so as to be substantially free from contact with the hot combustion chamber gases, said cleaning 105 fluid supply header having a branch pipe extending therefrom between said water circulating tubes and into the boiler combustion chamber, and a cleaning fluid discharge nozzle carried by the branch pipe and likewise located within the boiler combustion chamber for discharging a jet of cleaning fluid toward said steam generating tubes. 110

fluid supply header having a branch pipe extending therefrom between said water circulating tubes and into the boiler combustion chamber, and a cleaning fluid discharge nozzle carried by the branch pipe and likewise located within the boiler combustion chamber for discharging a jet of cleaning fluid toward said steam generating tubes, said cleaning fluid supply header, branch pipe and discharge nozzle being rotatable as a unit to change the direction of discharge of the jet of cleaning fluid from the nozzle.

5. In a boiler cleaner, the combination with spaced boiler tube headers, water circulating pipes connecting the same and steam

generating tubes extending at an angle with the water circulating pipes into the boiler combustion chamber, of a plate-like member extending between the said boiler tube headers with the water circulating pipes lying between the said member and the boiler combustion chamber, a cleaning fluid supply header, said member forming a bearing for said header, a branch pipe from said cleaning fluid supply header, and a discharge nozzle carried by said branch pipe within the boiler combustion chamber.

10. In testimony whereof I affix my signature.

FRANK BOWERS.
